United States Patent Office

Des. 228,975
Patented Oct. 30, 1973

228,975

UMBRELLA

Jeffrey Schertz, New York, N.Y., assignor to Schertz
Umbrellas, Inc., New York, N.Y.

Filed July 17, 1972, Ser. No. 272,100

Term of patent 14 years

Int. Cl. D3—03

U.S. Cl. D88—3 R

FIG. 2

FIG. 3

FIG. 1

FIG. 4

FIG. 1 is a perspective view of an umbrella showing my new design in a closed position;

FIG. 2 is a front elevational view thereof in an open position;

FIG. 3 is a side elevational view of FIG. 2, the opposite side being identical thereto;

FIG. 4 is a top plan view of FIG. 3.

I claim:

The ornamental design for an umbrella, as shown and described.
